UNITED STATES PATENT OFFICE.

CHARLES W. BRAYTON, OF WATERLOO, IOWA, ASSIGNOR TO WATERLOO CEMENT MACHINERY CORPORATION, OF WATERLOO, IOWA, A CORPORATION OF IOWA.

CONTROLLING MECHANISM FOR MIXING-MACHINES AND THE LIKE.

1,145,829.

Specification of Letters Patent.

Patented July 6, 1915.

Application filed December 6, 1913. Serial No. 805,015.

To all whom it may concern:

Be it known that I, CHARLES W. BRAYTON, a citizen of the United States, residing at Waterloo, in the county of Blackhawk and State of Iowa, have invented certain new and useful Improvements in Controlling Mechanism for Mixing-Machines or the like, of which the following is a description.

10 My invention belongs to that general class of devices known as mixing machines, particularly the type known as a tilttable batch mixer, consisting of an open drum suitably mounted on a swinging or tilting support.

15 The present invention consists particularly in an adjustable locking device for maintaining the drum in the desired position, as it is frequently desirable to vary the angle of the drum when in mixing position, depending upon the mixture in the same.

20 The invention has among its objects the production of a device of the kind described that is simple, convenient, efficient, durable, and satisfactory, that will not easily get out of order, and that may be manufactured at small cost, and used wherever found applicable.

25 To this end my invention consists in the novel construction, arrangement and combination of parts herein shown and described, and more particularly pointed out in the claims.

30 In the drawings, wherein like reference characters indicate like or corresponding parts, Figure 1 is an end elevation of one type of mixing machine with my invention applied thereto; Fig. 2 is an enlarged view in elevation of a portion of the same; Fig. 3 is a sectional view taken substantially on line 3, 3 of Fig. 2; Fig. 4 is a perspective view of the latch, and Fig. 5 is a sectional view through the drum and its support.

35 Referring to the drawings, the mixer shown comprises a frame consisting of the parts 1 and 2, which may or may not be mounted on wheels 3, and which carries standards 4, which carry the drum. This drum may be of any desired type, that shown comprising the parts 6 and 7 which form a drum opened at one end and closed at the other, the drum being rotatably supported on a shaft 8 carried by the tilting support 5. It is not necessary to describe the construction of the drum, or the method

of securing the same to its support, as this is fully described and claimed in a companion application. It may be mentioned, however, that the drum is preferably rotated by means of a driving pinion 10 engaging with the drum flange 9, formed with teeth for engagement therewith, the pinion being driven from a sprocket wheel 11, or any equivalent for the purpose.

40 The drum and its support are maintained in the desired position for mixing, or tilted to dump the mixture, preferably by one or more arms 15. As most clearly shown in Fig. 3, the end of the support 5 opposite the pinion 10 is provided with an extension 14, forming a stub-shaft either integral therewith, or separate, as may be desired.

45 This end is carried by the standard which is formed with a bearing 12, 12. Upon the end of the shaft part 14 is secured a plate 16, or its equivalent. This plate may be secured in position in any desired manner; as shown, it is secured and prevented from rotation on the end of the shaft by a bolt 17. Carried by plate 16 is an adjustable plate 18, which carries the arms 15. The plate 18 is preferably secured to the plate 16 by a plurality of bolts, as shown, three,—19, 20 and 21. The bolt 19 forms a pivot point, one plate, as shown, the plate 18, being 50 formed with slots 22, so that plate 18 may be adjustable relative to plate 16 about the bolt 19, as a center. Washers 23 may be provided if desired. There may be any number of arms 15, three being convenient for the purpose, and they may be secured to plate 18 in any convenient way. As most clearly illustrated in Fig. 2, the plate 18 is formed with sockets 24, one for each arm, and the arms secured therein by set screws 25, or in 55 any equivalent manner. Carried by the standard 4 is a bracket 26, formed with an extended part 27, (Fig. 4) forked to receive a latch 28. The latch 28 is pivotally secured at 29 to the bracket, and formed with a hook 30, adapted to engage with one arm 15, as shown in Fig. 1, when the drum is in 60 mixing position.

65 When mixing a batch of material, as for example, concrete, the mixer is thrown to the position indicated in Fig. 1, and maintained in that position by the latch 28, engaging one of the arms 15. If it is desired to vary the position of the mixing drum, the mixing bolts 19, 20 and 21 are loosened suf-

ficiently to permit shifting of the drum and plate 16 to the desired position relative the plate 18, that is, the parts may be locked in position at a steeper angle to that shown, or to a less, for clearness the parts being shown in the drawings in a midway position. The bolts are then tightened up, making plates 16 and 18 the same as one piece. In dumping, the latch 28 is moved 10 to release the arm 15, and the drum tilted to the opposite side of the standards to discharge the contents. It may be mentioned, in this connection, that the bracket 26 forms a convenient stop for the opposite 15 arm 15, limiting the movement of the drum. The attachment described permits the drum to be tilted at a steeper angle when a wet mixture is mixed in the drum than when a dry mixture, experience having demon- 20 strated that there are occasions when it is desirable to have the adjustment varied as described. While a drum is described open at one end and closed at the other, any tilted type of drum may, of course, be em- 25 ployed. In Fig. 1 is shown auxiliary supporting means for the drum through the shaft 8, this consisting of a plurality of rolls 32, suitably carried from the frame. How- 30 ever, this device is the subject matter of a companion application, and need not, there- fore, be described in detail in this applica- 35

Having thus described my invention, it is obvious that various immaterial modifica-

tions may be made in the same without de- 35 parting from the spirit of my invention; hence I do not wish to be understood as limiting myself to the exact form, construc- 40 tion, arrangement, or combination of parts herein shown and described, or uses men- tioned.

What I claim as new and desire to se- cure by Letters Patent is:—

1. The combination of a suitable frame, standards carried thereby, a tiltable U- 45 shaped member pivotally carried by said standards, a drum rotatably carried by said member, a plate rigidly secured to said member, a second plate adjustably secured to said first mentioned plate, an arm car- 50 ried by said second plate, and a coöperating latch member for said arm carried by one of said standards.

2. The combination of a suitable frame, standards carried thereby, a tiltable U- 55 shaped member, pivotally carried by said standards, a drum rotatably carried by said member, a plate rigidly secured to said mem- 60 ber, a second plate adjustably secured to said first mentioned plate, and an arm car- ried by said second plate.

In testimony whereof, I have hereunto signed my name in the presence of two sub- scribing witnesses.

CHARLES W. BRAYTON.
